LOUIS KRUG, JOHN P. WEIS, AND WILLIS C. ROBBINS, OF NYACK, NEW YORK, ASSIGNEES, BY MESNE ASSIGNMENTS, TO LUCIUS N. LITTAUER, OF GLOVERSVILLE, NEW YORK.

FOLDER FOR COLLARET-MACHINES.

1,230,906.

Specification of Letters Patent. Patented June 26, 1917.

Application filed August 6, 1906. Serial No. 329,356.

To all whom it may concern:

Be it known that we, LOUIS KRUG, JOHN P. WEIS, and WILLIS C. ROBBINS, citizens of the United States, residing at Nyack, county 5 of Rockland, and State of New York, have invented a new and useful Improvement in Folders for Collaret-Machines, of which the following is a specification.

This invention relates to folders for sewing machines, and particularly to that class 10 of folders, or cloth-turning devices, which are adapted for manipulating a "collaret," or strips of similar material.

Among the objects of this invention, the following may be noted: to provide a folder which will manipulate the binding material, such as is used for Balbriggan and other undershirts; so that it will be accurately guided and fed to the stitching point or position of a sewing machine with its edges properly and evenly hemmed or folded so that it may be attached to the body material of a shirt along the neck-opening thereof; to provide a folder, for attachment 25 to a sewing machine, of a construction such that it will properly manipulate a collaret or binding material, receive the edge of the body material, and present the two materials in proper condition and juxtaposition for connection by a line, or lines, of 30 stitching passing through the hemmed edges and the body material; to provide a folder of such construction that it may be applied to the work-plate of practically any machine without obstructing the view of the operator in front of the stitching position, and so as to present the material to the 35 stitch-forming mechanism directly in the line of feed; to provide a folder which is adaptable to a collaret machine of practically any style and which is placed on the machine at a right-angle to the line of feed, with its delivery end parallel with the feed; to provide a folder for binding materials of 40 all kinds with a tension-device operating upon the edges of the binding so as to stretch the same, in order to make the edges operated upon of greater radius, thus giving the proper curvature for rounding the neck-opening of a shirt, for example, to which the binding is applied; to provide a folder 45 for manipulating collarets so as to allow the body of the latter to pass freely through the folder with substantially no stretch, and so as to apply tension to the folds of the hems 50 55

of the collaret at the delivery end of the folder; to provide a folder for manipulating binding materials having a construction such that said binding is led close up to the stitching point and the presser-foot, 60 so that the latter may receive under it the entire width of the hemmed binding material, and thus avoid staggering the binding and any tendency to draw the hemmed edges away from the stitching mechanism; 65 to provide a folder, for manipulating bindings, with means whereby to prevent the extreme edges of the binding which are being hemmed, from curling, and, generally, to place such tension upon the binding material at the hems as to locate the fold properly and limit the flow of the collaret through the folder and guide it uniformly; 70 to provide a folder, of the class described, with means whereby to perfectly control the disposition of the stripe or tuck-stitch which may be produced in the manufacture of the collaret, or binding materials, so as to cause said stripe or tuck-stitch to take its proper place on the edge of the neck of the garment during the application of the collaret to the latter; to provide a binding-guide 75 with new forms of uncurling devices, specially adapted for collaret work, or work of similar character; to provide a folder 80 which can be made from sheet or blank material for cheapness of manufacture; and to provide other minor features of improvement and importance for manipulating a binding of any character so as to guide the 85 same and properly lead it up to the stitching position with its edges hemmed or turned ready for application to the body material. 90

With the above objects in view, and others 95 which will be detailed during the course of this description, our invention consists in the parts, features, elements and combinations of elements hereinafter described and claimed. 100

Referring to the drawings, forming part of this specification,

Figure 1 is a front end elevation showing portions of a sewing machine with a folder secured thereto and the relation of the tension and guiding device delivering the binding material to the folder, the edges of the binding material being shown turned or hemmed at the delivery end of the folder to illustrate the manner in which the con- 110

trolling wires operate upon the edges as the binding makes its angular turn and is fed under the presser-foot to be stitched to the body material;

5 Fig. 2 is a top plan view of a portion of a sewing machine, showing one form of folder secured thereto and the relation of the tension and guide to the folder, portions of the figure being broken away to 10 show the manner in which the binding is manipulated;

Fig. 3 is a front elevation of the folder shown in Fig. 2;

15 Fig. 4 is a rear elevation of the folder with a strip of binding material shown therein, the form being that of Fig. 3;

Fig. 5 is a top plan view of the blank from which the folders are made;

20 Fig. 6 is a top plan of the mouth-blank as made separate;

Fig. 7 is a top plan of the tail-blank as made separate;

25 Fig. 8 is a top plan of another form of the folder, showing the binding material therein;

Fig. 9 is a front elevation of the form of folder of Fig. 8;

30 Fig. 10 is a section on the line 10—10 of Fig. 3, looking in the direction of the arrows;

Fig. 11 is a front view of a portion of the tension device;

Fig. 12 is a front view of the tension holder; and

35 Fig. 13 is a side elevation of the tension holder.

Primarily, it should be understood that folders of the character made the subject of this invention are specially intended and 40 adapted for the manipulation of what is known as a French collaret which, during its traverse through the folder, has its edges turned or hemmed so as to be properly applied to the neck-opening of a Balbriggan 45 undershirt. It should not be understood, however, that this class of work indicates a limitation in the functions of the folder, or in its capability of manipulating other styles of collarets and bindings of all character, as the structure of our folder is such 50 that the latter is capable of guiding and properly manipulating bindings of all character, for the purpose of hemming the edges thereof and applying the same to another 55 piece of work. Therefore, it is to be distinctly understood that the features of improvement which will be hereinafter described and claimed are applicable to folders broadly, and without regard to the particular material to be passed through the same, although the features of our invention have been developed especially in connection with knit goods, or goods which are stretchy or elastic.

60 The structure of the present application

is especially adapted for manipulating certain styles of collarets, which have been recently developed in the trade, and which are now in great demand; that is to say, collarets, as made by certain manufacturers, are provided with salient or ornamental ridges, or ornamental stitches, in the body thereof extending longitudinally of the material, the same being formed usually from colored yarns by what is known in the art as a "tuck-stitch". The ridges thus formed constitute impediments to properly manipulating the collaret, and prevent, oftentimes, its proper application to the body material. In other words, in applying the collaret, made as above noted, to the edge of the neck of the garment, it is essential that the said ridges or stripes made by the tuck-stitch, or otherwise formed, shall be uniformly disposed, either directly on the edge of said neck, or uniformly spaced from the folded edges of the collaret; but, it has been found that, in leading in the collaret, the latter is liable to sag to the bottom of the folder, resulting in causing the said stripe or ridge to sag away from the central line of the folder or of the collaret and, consequently, sag away from the edge of the neck-opening of the garment, thus running down the side of the neck, either on the outside, or the inside of the garment. It also often happens, in the manufacture of the collaret or other binding strip, that the stripe or ridge may be produced in waved lines or, in cutting the collaret into strips, the said stripe or ridge may not be exactly centrally disposed between the two edges thereof. In either of these cases, the difficulties just above noted, with reference to leading in the collaret and bringing the said stripe or ridge exactly at the edge of the neck of the garment, or at a uniform distance from the hemmed edge of the collaret, will be met with. In all these cases, if the collaret cannot be properly applied to the body material, it will be necessary to either throw away material portions of the collaret, thus producing expensive waste, or, if the collaret has been applied to the garment, the latter cannot be disposed of to the first-class trade. The above difficulties are all overcome, and waste is avoided, and the garments are saved by the use of the folder or binder produced by us, and which is made the subject of this application; and, with such folder or binder, we are able to perfectly control the disposition of the stripe or ridge either on the edge of the neck of the garment, or uniformly with reference to the hemmed edges of the collaret, as will be presently described. Other special advantages of features of the folder about to be described will be set forth, in connection with their mechanical details, during the course of this description.

For brevity, we purpose, throughout the

description and claims, referring to the material manipulated by the folder as the "binding," and we intend that this term or expression shall comprehend collarets and all or any kind, style or class of binding, irrespective of its structure or texture, or the material of which it is made; and we also purpose referring to the article, work or material to which the binding is applied as the "body-material" and intend that this term or expression shall comprehend any material to which the "binding" may be applied, whether it be in garment form or not.

Upon reference to the drawings, the structure of our folder will be readily understood, and in said drawings, and with special reference to Fig. 5, it will be seen that the body-portion of the blank of the folder is indicated by the numeral 1, which body-portion 20 may have formed integral with it an extension 2, shown in dotted lines, which forms the tail of the folder. As shown in Fig. 7, said tail may be a separate blank. The numeral 3 indicates side extensions 25 which, at their forward portion, are separated from the body-portion, said extensions 3 having their outer edges 4 straight, their outer ends 5 at an obtuse angle to their outer edges, and their inner edges forming an acute angle with the ends 5, said inner edges 30 terminating in substantially a semi-circle so as to help form a large space 7. This space, when the blank is formed into a folder, not only facilitates the formation of the uncurler 14 hereinafter described, but enables 35 that part of the folder to the rear or to the right of this space in Fig. 2 to be flat or vertical, thereby to feed a strip vertically, and the front portion or that part of the folder to the left of the space in Fig. 2 to be 40 properly bent upon itself so as to fold the strip upon itself. In other words, this space not only forms a dividing line between the straight portion of the folder where the strip is fed substantially vertically and the bent portions of the folder where the strip 45 is turned upon itself, but as stated, materially facilitates the proper formation of the folder to enable it to feed the strip in the manner indicated, while it also facilitates 50 the proper disposition of the loop forming members 8 and the extensions 3. It is also advantageous in the handling of the strip to enable the operator to see exactly the manipulation of the strip by the folder and may also be used to facilitate the insertion 55 of the strip in the folder. The body 1 of the blank is formed with loop-forming members 8, each provided with short extensions 60 9 near the forward end, and each also having its outer end substantially V-shaped in form, as indicated at 10, and the body of the blank being also V-shaped at its end reversely to the ends of the loop-forming members, as 65 shown at 11. The outer edges 12 of the loop-

forming members 8 are given an ogee curvature extending from the extensions 9 to the space 7, at which latter the line of said edges is extended at substantially a right-angle to form a V-shaped notch 13 and a lip 14 which forms, in the completed article, an auxiliary uncurler, as will be described. To produce the folder shown in the several figures, the blank 1 is folded along the several lines 15, so as to turn the extensions 3 over upon the body 1, and then the loop-forming members 8 are folded over on the lines 16, so as to inclose the extensions 3, all of which will be readily understood upon reference to Figs. 2, 3, 8, 9 and 10. When the folder is thus formed, the lugs 9 of the loop-forming members 8 are bent down upon the extensions 3 near the forward end of the latter and solder is applied so as to form the connection 17, shown in Figs. 3 and 9, to thus give support 75 to the extensions 3, at their outer ends, which extensions form tongues within the loops 8, said tongues and loops starting and forming the fold in the binding material to properly hem the edges of the latter. The lips 14, 80 formed at the junction of the loop-ports 8 with the body-portion 1, are then bent slightly inwardly, as shown in Figs. 2, 4 and 8, toward the extensions 3, thus causing said lips 14 to project into the space 7 and stand 85 in a position to receive the curl of the binding and lift the edge of the latter so as to give it the proper direction through the folder and form the hem of the binding. Now viewing Fig. 6, the blank which forms 90 the mouth-piece or outlet-end of the folder will be readily understood, the body of said blank being indicated by 18, said blank being given a substantially triangular form so as to fit in the V-shaped end 11 of the 100 body-blank 1, as shown by dotted lines in Fig. 5. When the folder is formed, the blank 18 is doubled upon itself and soldered, for example, into position so as to become 105 an integral part of the folder and extend at 110 a right-angle, substantially, to the loop-ports 8 of the folder, the concavity of the mouth-piece being presented outwardly as shown in the several figures.

Referring now to Figs. 8 and 9, it will be 115 seen that the mouth-piece 18 of the folder extends beyond the back of the latter a slight distance, as shown at 19. The edges 4 of the extensions 3 are brought into separated position, as shown in Fig. 9, and are thus maintained by means of a bridge-piece 20 properly soldered in place so as to brace said extensions and hold them separated from the back of the folder to provide a free passage for the binding through the folder at the 120 inlet-end 21 thereof, the channel or slot 22, thus formed between the edges 4 of the extensions 3, permitting an instrument to be engaged with the binding for starting the end of the same through the folder. A 130

4 tension-device, which coöperates with the binding material at the folds thereof to exert tension and create drag on the collar at the folds, is secured to the folder by means of a 5 holder, the horizontal base-portion 23 of which spans the channel or slot 22 of the folder and is soldered, or otherwise rigidly secured, to the extensions 3, so as to hold the tension-device centrally of the folder. The 10 tension-holder also has the portion 24 extending at a right-angle to the base 23, the upper end of which portion 24 is provided with an aperture 25, threaded for receiving the screw 26. The base 23 is provided with 15 the pairs of wings 27, separated by the recess 28, these wings being made sufficiently thin to be flexible, and thus capable of being bent over, as shown by dotted lines 29, Fig. 13, and clamped upon the straight portions 30 20 of the tension-device. Thus, when the wings 27 are closed over the portions 30 of the tension-device, the latter is journaled in the base 23, so as to rock thereon. Between the portions 30, the tension-device is extended 25 at a right-angle to provide the bar 31, which, in the instance shown, is in loop-form, the same coöperating with the forward, reduced end 32 of the screw 26, said end passing into the slot 33 of the bar 31 and having its 30 shoulder 34 in engagement with the back of the bar 31, as clearly shown in Figs. 8 and 9. Thus, the screw 26 is enabled to rock the tension-device in its bearing in the base 23, so as to place more or less tension upon the 35 forwardly-extending tension-arms 35 which, in the instance shown, are given a bowed or curved form and extend forward within the loops 8 of the folder, and to substantially the forward end of the tongues 3, so as to 40 lie within the fold of the hems and create tension or drag on the latter by pressing the binding material at the folds of the hems against the bends of the loops 8, as clearly represented in Figs. 8 and 9. Whatever may 45 be the adjustment of the screw 26 for exerting the proper degree of tension upon the arms 35 of the tension-device, said adjustment will be maintained, or the screw held set by means of the binding-nut 36, which 50 turns upon the screw 26 and engages the back of the part 24 of the tension-holder. The particular and important function of this tension-device is to create drag upon the hems, or edge-folds, or edges of the binding, 55 so as to stretch the same and give a greater radius thereto, thus imparting a circular form to the binding as it leaves the folder and giving to the finished work a circular or rounded form.

60 It will be noticed that the mouth-piece 18 is secured to the delivery-end of the body-portion of the folder in the space between the ends of the opposite loop-portions 8, substantially at a right-angle to the length of 65 the said folder, thus compelling the binding,

in its passage through the folder, to turn abruptly at a right-angle, so as to be delivered in the line of the feed, as shown in Figs. 2, 8 and 9. At the delivery-end of the folder, and coöperating with the latter and said mouth-piece 18, controlling-guides 37 are provided, which operate on the folded edges of the binding to reduce and prevent undue drag of the latter at the delivery-end of the folder proper, as said binding makes its angular turn. Referring to Figs. 2 and 3, which show one form of the controlling-guides, it will be seen that the latter consist preferably of substantially semi-circular pieces of round wire, soldered, or rigidly secured, in place at opposite ends to the outer portions at 38 of the loops 8 of the folder and to the mouth-piece 18 as at 39, said guides being extended, with considerable divergence across the delivery-end of said loop 8, as clearly shown in Figs. 1 and 2. In Figs. 8 and 9, another form of controlling-guides is shown, one end of each of which is secured to the outside of one of the extensions or tongues 3 near the outer end 90 thereof, as at 40, and extends from the said point of attachment forward toward the delivery-end of the folder, so as to provide a straight portion 41 extended substantially parallel with the delivery-end of the loop-portion 8 of the folder, and at the extreme end of said loop-portion said guide is bent around the latter to form the loop 42 and back upon the said loop-portion 8 of the folder, and secured to the latter, or the mouth-piece 18, by soldering or otherwise, as at 43, Fig. 10, in order to make a rigid connection. Thus, the guides are caused to diverge slightly from the point of attachment 43 to the point of attachment 40, but not to the 105 same extent as in the form of Figs. 1, 2 and 3. The disposition of the controlling-guides, as shown in the several figures, at the delivery-end of the folder, is an important feature of our invention and, upon it, we desire 110 to lay considerable stress, in that they reduce the drag and tension upon the binding-material, as the latter makes its angular turn in the throat 8, and also prevent the extreme edges of the binding from curling by keeping the same substantially flat, as shown in Figs. 8 and 9, and prevent the flow of the binding beyond the end of the folder, guide it uniformly during its passage through the mouth, and by their divergence provide a 115 wide entrance for the body-material at the delivery-end of the folder.

The extension 2 operates as the primary uncurler for the material and prevents the same from going into the inlet-end 21 of 120 the folder in curled condition, this function of said extension 2 being performed by reason of the fact that its outer edges are narrowed down to the comparatively narrow end 44, which is considerably narrower than 130

the strip of material passing through the folder. When it is understood that the natural tendency of the binding-material is to curl over, as shown in Figs. 8 and 9, or to 5 cling around the edges of the extension 2, it will be apparent that the end 44 will always be centered in the binding-material, between its curled edges, and the latter will be gradually straightened out into flat position 10 as the binding is led through the folder, so as to cause said binding to enter the inlet-end 21 of the folder substantially flat, as shown in Figs. 8 and 9. This extension 2 may be made separate from the body-blank 15 1, as shown in Fig. 7, and soldered in position, or may be made integral with said body-blank.

By comparing the form of Figs. 1, 2, 3 and 4 with that of Figs. 8, 9 and 10, it will be 20 seen that there is a material difference in the structure of the folder as a whole and its combination with the mouth-piece 18; that is to say, in the first group of figures, the loop end of the folder stands at a considerably less angle relatively to the body-end, than in the second group of figures, because, in order to adapt the folder to manipulate binding-materials of narrow width, it is made much smaller and the loop-end does 30 not have to be bent at much of an angle to the body-end, hence, bringing the delivery-end of the folder more in line with the entry-end; but, when wide bindings are used, the loop-end must be made larger, resulting in 35 setting the loop-end at quite an angle relatively to the body-end. In other words, differences in sizes of binding, beyond certain limits, necessitate a change in the size of the folder, and beyond certain normal or general sizes, a change in size of the folder, accordingly as to whether the size is increased or reduced, resulting in bending the folder as described at more or less of an angle, carry the delivery-end of the folder more 45 or less away from the stitching position, and necessitate changing the size of the mouth-piece 18 in proportion to the extent to which the same must be projected beyond the delivery-end of the folder in order to 50 properly lead the binding clear up to the stitching position, or path of reciprocation of the needle. These changes in the size of the folder and of the mouth-piece are necessary in order to maintain and secure the 55 same relative position, in all cases, of the mouth-piece and path of the needle or stitching point so as to guide said binding and properly present it for the line of stitching in the hems thereof. In all other respects, 60 the body-portion of the folder, including the tongues 3, the loops 8 and the lugs 9, is substantially the same in all the figures.

In the form of folder shown in Figs. 1, 2, 3 and 4, the inlet-end has been modified; that 65 is to say, instead of being provided with

the uncurling extension 2, shown in Figs. 7, 8 and 9, the folder is provided at its inlet-end with a rest or support for the collaret, so that the latter may be properly led into the folder at the inlet-end, the said support 70 consisting of the bar 45 having its ends turned at an angle thereto to provide the end-portions 46, the inner ends of which are soldered or otherwise connected at 47 to opposite sides of the body-end at the inlet-end thereof. This support is located substantially in the plane of the passage for the binding-material through the folder, as clearly shown in Fig. 2, said bar 45 being thus in position such that the binding, in 75 passing thereover, will be led directly into the entry-end 21 of the folder. This form of support, in addition to being a guide, tends to prevent the binding from wrinkling and curling, being thus practically an uncurling device also. This form of support is intended to be used in cases where the binding-material is placed under tension between the inlet-end of the folder and reel 80 upon which it is wound. When the binding is placed under tension, as just suggested, it is only necessary to use a support 45, such as shown in Figs. 2 and 3, which will maintain the said collaret, in its passage from the tension-device to the inlet-end of the folder, 85 in its flat form and prevent its edges from curling in the wrong direction between the tension-device and the inlet-end of the folder. In this connection it should be borne in mind that the natural tendency of the binding-material is to curl so as to throw the wrong side outside and that it is the object of the uncurling device 2 and the combined uncurling device and support 45, combined with the tension applied as suggested, 90 to prevent the curling in the wrong direction. Thus, by interposing the said devices between the tension-device and the inlet-end of the folder, the natural tendency to curl in the wrong direction may be overcome. 95 Preferably, the bar 45 of the support over which the binding-material passes is straight, and the entrance-end 21 of the folder is also substantially straight, and the said bar of the support is preferably disposed as above described in connection with 100 Figs. 2 and 3.

Reference has been made to the lips 14, which act as auxiliary uncurlers and operate upon the edge of the binding passing through the folder; that is to say, referring to Figs. 4, 8 and 9, it will be understood that, if any portion of the binding should pass the inlet-end with its edge or edges 105 curled in the wrong direction, as at 48, Fig. 4, said curl will pass to the space 7, and straddle, or run upon, the uncurling lip 14, which is bent toward the extension 3, so as to close the binding passage sufficiently to 110 prevent the increased thickness of the curled 115 120 125 130

edge from passing into the loop-portion of the folder. The curled edge will thus be received upon the lip 14 and will ride up the curved edge 12 of the loop-portion 8 and be gradually flattened, then turned over in 5 the proper direction by the said edge 12 and upon the edge 6 of the extension or tongues 3, thus properly starting and forming the hem in the edges of the binding. Hence, if 10 the primary uncurlers should happen to allow a curled edge to pass, the auxiliary uncurlers will certainly uncurl said edge. As before stated, with the form of combined support and uncurler 45, a combined guide 15 and tension-device is commonly employed, the same consisting of the base or stand 49, Fig. 1, carrying a spindle 50, adjustable in said base by a clamping-screw 51 the upper end of which spindle is provided with a 20 channel-bar 52, in which is set a spindle-bar 53, carrying a series of spindles 54, said spindle-bar being clamped in the channel-bar by the thumb-screw 55. The spindles 54 are spaced so that the binding may pass 25 without undue friction between them, but tension is applied to said binding by passing the latter around and between two or more of said spindles according to requirements. This construction is merely an example of a 30 means for guiding and applying tension to a binding, said means being usually disposed between the binding reel and the inlet-end of the folder.

In connection with the folder of our invention, in all its forms, we employ a device which we term a strip-controller, the same consisting of the cross-bar 56 soldered or otherwise rigidly secured to the folder so as to extend transversely across the slot 22 thereof, and two oppositely-disposed controlling-fingers indicated by 57 secured to said cross-bar 56 by means of the screws 58 passing through the elongated slots 59 in said fingers 57 at one end and tapped into 45 the ends of the cross-bar 56. This provides for the longitudinal adjustment of said fingers 57 and also permits a sidewise adjustment or pivotal movement upon the screws. The fingers are secured in position such that 50 they will converge toward the delivery-end of the folder and are sufficiently long to permit their forward ends, toward which said fingers are also tapered, and may be slightly curved, as clearly shown in Figs. 2 and 3, to 55 be positioned within the loops 8 of the folder. The two adjustments of the controlling fingers 57 just described are provided for the purpose of adjusting the forward end of the fingers toward and from 60 the bend of the loops and longitudinally of the latter, in order to maintain the ends of the fingers always flush or nearly so with the delivery-end of the folder, irrespective of the lateral position or adjustment of said 65 fingers relatively to the fold of the loops. It

will be understood that, as the edges of the binding are folded over by the said loops 8 and tongues 3, said edges will engage one edge of the said fingers and, according to the adjustment of the latter, the position of 70 the binding in the folder will be perfectly controlled. Thus, by laterally adjusting the said fingers, which constitute a duplex guide the binding may be pushed one way or another in the folder, transversely thereof, in 75 order to bring the said ornamental stripes or ribs formed by the tuck-stitch in the exact position desired. It will also be seen that, if it is intended that the said stripes shall be located in a given position with reference 80 to the edges of the binding,—the hemmed or folded edges,—said position can be both accurately determined and perfectly maintained throughout the operation of applying the binding to the edge of the body 85 material.

In Figs. 2, 3, 8 and 9, we have shown a supporting or attaching means for the folder which, briefly, consists of the supporting-plate 60 secured to the lower tongue 90 3 of the folder in any permanent manner, substantially parallel with the slot 22, which supporting-plate carries the extension 61, at an angle thereto, which in turn carries the attaching-plate 62, which extends substantially 95 parallel with the supporting-plate 60. The attaching-plate 62 is provided with the elongated, open-end slots 63 for receiving the shank of the attaching thumb-screws 63^a, Fig. 2, for securing the folder in place upon 100 the machine. Further details of this attaching means have not been shown nor described, as the same forms the subject matter of a patent granted to Louis Krug, June 7, 1910, #960,345. 105

From the above detailed description, the structural and mechanical features of the folder will be readily understood; but, it must be borne in mind that the binding-material is ordinarily wound upon a reel in 110 long lengths and is delivered therefrom by being dragged or fed through the folder by means of the feeding mechanism of the sewing machine. As above indicated, the combined binding-guide and tension device is 115 located between the binding reel and the inlet-end of the folder. This device must be distinguished from the tension-device which operates upon the edges or hems of the binding and the functions of which latter have been clearly set forth above. The principal objects of the binding-guide and tension are to keep the binding from curling between the reel and the folder and to present said binding to the folder at the proper level. 120 Hence, the guide should be so adjusted that its spindle-bar surface will be on a level with the lower edge of the inlet-end of the folder (the latter being held vertically on the machine) so that the lower edge of the 125

binding will be prevented from sagging, curling or dragging on the lower edge of said inlet-end. The tension applied to the binding by the spindles 54 is uniform throughout the width of said binding and stretches the latter longitudinally, thus tending to prevent the edges curling and also presenting the binding at the inlet end of the folder in such condition that it will run in smoothly and freely. If the guide and tension fails, for any reason, to properly perform its functions, the primary uncurling devices and the auxiliary uncurling devices will, in turn, operate upon the edges of the binding so as to properly pass the binding to the stitching position.

When narrow bindings are employed and the form of folder of Figs. 2 and 3 is used, the folder is adjusted on the cloth-plate of the machine with the mouth-piece 18 close up to the stitching position represented by the path of the needle 65, and close to the toe 66 of the presser-foot 67, in order that the hemmed binding may be guided by the inner edge of said toe between the mouth-piece 18 and the broadened body 68 of said foot, see Fig. 2, and so also that the body-material may be delivered at the same time directly from the said mouth-piece to the stitching mechanism. When the folder of the form shown in Figs. 8 and 9 is used, the delivery-end of the folder is adjusted so as to place the throat-portion 19 close up to the stitch-forming mechanism and presser-foot, as just described with reference to the other form. When the form of Figs. 8 and 9 is employed, the extension 2 of the folder acts as an uncurler, this becoming necessary, however, only when a tension-device in connection with the folder is employed. If said guide is employed, the extension 2 of the folder will operate as an auxiliary and lead the binding in smooth and without curl, wrinkle or fold. The binding being passed into the inlet-end of the folder, the same will be worked down to the loops and tongues of the folder by means of an instrument inserted in slot 22, and then conveyed through the mouth-piece so as to start the folder in operation, and when the latter has fairly begun, the edges of the binding will be folded by the tongues and loops 3 and 8, respectively, and the edges thus turned or hemmed will be conveyed into the mouth of the folder, as shown in Figs. 2 and 8, by changing the direction of travel of the binding so as to deliver the same from the mouth at a right-angle to its passage through the folder, the angle formed at the junction of the end of the body-portion with the throat determining and making the central line of fold of the binding, which is indicated by *x*. The guides 37 or 41, the tension-arms 35 and the controlling-fingers 57 performing their functions upon the binding-material in the manner already described, so as to direct the same properly through the folder and the throat, create the necessary drag at the proper points and deliver the binding and body-material to the stitch-forming mechanism and presser-foot in the condition required for neat and sightly work. The guides 37 or 41, in addition to the functions already described, prevent the extreme edge of the hemmed binding from curling, in that they keep said edges substantially flat for delivery in that condition to the stitch-forming mechanism. The points formed by the edges 5 and 6 of the tongues stand in the fold or hem of the binding at the delivery-end of the folder and properly locate the fold of the hem.

In addition to the advantages already set forth during the course of the above detailed description, and which are also included in the statements of objects of the invention, the following will be apparent: The folder can be made of a single piece or blank of material, which makes it cheap and simple to manufacture; the blank can be made with or without the mouth and tail pieces 18 and 2, respectively, according to the nature of the use of the folder; the folder, by reason of its structural features, is capable of handling all kinds of bindings and manipulating them in such wise as to present them to the stitching point and lead them under the presser-foot with only such stretch or tension as is necessary, and without curl in the edges thereof; by providing the adjustable tension-device for application of tension or drag upon the hem of the binding at the delivery-end of the folder, the proper curved or rounding effect can be produced, which is essential in many instances, as, for example, in applying collarets or other bindings to the necks of undershirts, or other curved outlines; and the adjustment of the tension-device being under the control of the operator, the tension can be adjusted during the operation of the machine, accordingly as the observations of the operator dictate the necessities; by providing the adjustable edge-gage for the binding-material, the stripe or tuck-stitch can be properly directed at all times, as the binding is running through the folder, so as to apply the binding with the said stripe at the proper distance, either from the edge of the binding, or the hem of the binding, and this feature of the invention also establishes a limit on both sides of the line of fold of the binding for the lateral movement of the latter in the folder, so as to prevent the same from sagging and running off during its application to the body-material, this also enabling varying sizes of bindings to be run through the folder without altering or replacing the latter; by providing the controlling-wires at the delivery-end of the folder, the

hemmed edges of the binding are held in position and made to pass through the mouth of the folder smoothly and uniformly, thus also preventing the hem from 5 varying in width between the turn from the delivery-end of the folder to the stitching position, and this feature also has the advantage of preventing the hemmed edges from running out too far beyond the delivery-end of the folder and thus compels the proper disposition of the line of stitching relatively to the edge of said hem; by providing the primary and auxiliary uncurlers, the material is compelled to travel 10 through the folder in proper condition and is prevented from reaching the loop-portions of the folder in any but the right condition, that is, while the primary uncurler will ordinarily uncurl and straighten out 15 the edges of the binding, if a curled portion should pass said primary uncurler, the auxiliary incurlers will surely remove the curl and turn the edges of the binding into proper direction for producing the hem formed by 20 the loops and tongues; hence, an improved form of the folder is produced, which eliminates, practically, every difficulty which has been discovered in connection with the application of bindings of all kinds to body- 25 materials and the several features of construction above detailed have been found to operate to perfectly apply the binding-material under every possible adverse condition; the interposition of the combined guide 30 and tension-device between the reel and the inlet-end of the folder, or adjacent the latter, makes it possible to lead the binding-material in flat form to the inlet-end of the folder, as well as place such tension thereon 35 as may be necessary to prevent the same from sagging and falling away from the folder and dragging in the lower portion thereof; and, by arranging the folder on the cloth-plate of the machine in a vertical 40 position and at a right-angle to the feed, with the mouth of the folder substantially parallel with the feed, it is possible to properly manipulate the binding and body materials without occupying so much space in 45 advance of the stitching mechanism as to practically obstruct and hamper the operator, this being a great fault in machines employing folders of this character, which are necessarily made quite large in order 50 to properly handle the work, and it will also be noted that our folder is arranged partially below and partially above the surface of the work-plate with the delivery-end of the folder and of the mouth-piece substantially 55 in the plane of the surface of the work-plate, thus enabling the feed to properly engage the combined materials without drag upon the latter, or tension upon the feed-dog, this general disposition of the 60

parts being an important feature of our 65 invention and a great desideratum in connection with this class of work.

Having thus described our invention, what we claim and desire to secure by Letters Patent is:

1. In combination, stitch-forming mechanism, feeding mechanism, and a folding-device, the latter comprising a flat body-portion tapered at its forward end, and the latter having an integral mouth-piece fixed 75 thereto and arranged substantially at a right-angle to its delivery-end and substantially parallel with the line of feed.

2. In combination, a stitch-forming mechanism; a feeding mechanism; and a folder, 80 the latter being arranged on the work-plate of the machine at a right-angle to the line of feed and wholly at one side of the latter, and comprising a flat body-portion vertically disposed on said work- 85 plate and having its forward end tapered, and the latter having an integral mouth-piece fixed thereto and arranged substantially parallel with the line of feed.

3. A folding-device comprising a body-portion having at one end hem-turning devices including loops having tongues suspended therein, in combination with a tension-device for co-operating with the folds of the binding-material within the hem-turning 95 devices at the delivery-end thereof.

4. A folding-device comprising a body-portion having at one end hem-turning devices, in combination with a tension-device for operating upon the folds of the binding 100 within the hem-turning devices, and means for adjusting said tension-device.

5. A folding-device comprising a flat, tubular, body-portion having a tapered hem-turning device at one end, in combination with an integral mouth-piece fixed thereto at said end at an angle to the said body-portion.

6. A folding-device comprising a body-portion having at one end hem-turning devices including loops having tongues suspended therein, and edge-controlling devices supported by the body-portion between and extending into the loops of the hem-turning devices, for operating upon the hemmed 115 edges of the material passing through the folding-device.

7. A folding-device comprising a body-portion having at one end hem-turning devices, and a duplex guide, for controlling the position of the edge of the binding passing through the folding-device, arranged between the hem-turning devices and having its guiding devices extending into said hem-turning devices.

8. A folding-device comprising a body-portion having at one end hem-turning devices, in combination with an edge-guide for

- operating upon the edge of the binding supported by the body-portion between the hem-turning devices, and means for adjusting said edge-guide.
- 5 9. A folding-device comprising a body-portion having at the inlet end thereof a primary uncurling-device and having at the other end hem-turning devices, and also having between said hem-turning devices and 10 the inlet-end auxiliary uncurling-devices, the uncurling devices operating oppositely from the hem-turning devices.
- 10 10. A folding-device comprising a body-portion having at one end hem-turning devices, comprising loop and tongue portions, 15 in combination with an uncurling-device carried by one of said portions and extending therewith toward the other of said portions.
11. In combination with a folding-device 20 having hem-turning devices including loops having tongues suspended therein, a tension-device carried by said folding-device comprising a pair of yielding arms inclosed by and operating within the hem-turning devices.
12. In combination with a folding-device 25 having hem-turning means including loops having tongues suspended therein, an edge-guide carried by said folding-device, comprising a pair of fingers extending longitudinally of and inclosed by said hem-turning means.
13. A folding-device having at one end hem-turning means, and at the other end 30 edge-uncurling means, said folder also having, at the junction of its body-portion and hem-turning means, auxiliary edge-uncurlers, the uncurling devices operating oppositely from the hem-turning devices.
14. In combination with a folding-device, 35 a tension-device for operating upon the hemmed edges of the binding, comprising a base-portion provided with a body-portion at an angle thereto, a tension-device journaled in the base-portion, and adjustable means carried by the body-portion and co-operating with the tension device for regulating the tension thereof.
15. A folding device comprising a body-portion having means, for folding a strip of material, at one end; hem-turning devices 40 carried by said folding device; and a guide, for controlling the position of the edge of the binding passing through the folding device, arranged in the passage for the material, and having its guiding device extending into said hem-turning devices.
16. A blank for a sewing machine folder 45 comprising a body portion having opposite side extensions separated from the forward end of the said portion by slots, said blank having a part adapted to form uncurling means at the inner ends of said slots when the blank is folded.
17. A blank for a sewing machine folder 50 comprising a body portion having opposite side extensions provided with substantially straight outer edges, the forward ends of which are separated from said body portion by slots, each of said extensions having its free end located substantially at an obtuse angle to its outer edge, and said body portion having at its forward end a substantially V-shaped recess which, together with the angular formation of the ends of the extensions, form when the blank is folded means to permit the strip to be inverted or turned inside out.
18. A blank for a sewing machine folder 55 comprising a body portion having connected therewith two extensions at each side thereof, each of said extensions having an inclined edge both extending in the same direction.
19. A blank for a sewing machine folder 60 comprising a body portion having connected therewith two extensions at each side thereof, one separated from the other by a slot, both extensions at each side of the body portion having inclined ends extending in the same direction and the said body portion having a substantially V-shaped recess at the same end.
20. A blank for a sewing machine folder 65 comprising a body portion having connected therewith two extensions at each side thereof of one separated from the other by a slot, each of said slots at the inner end thereof terminating in a part adapted to form when the blank is folded an uncurling device.
21. A blank for a sewing machine folder 70 comprising a body portion having connected therewith two extensions at each side thereof one separated from the other by a slot each of said slots terminating in a part adapted to form when the blank is folded an uncurling device and said body portion having a substantially V-shaped recess at its forward end.
22. A sewing machine folder comprising 75 a body portion having at one end hem turning means, an edge guide carried by the folder for operating upon the edge of the binding operated upon by the hem turning means, and tension means also carried by the folder.
23. A sewing machine folder comprising 80 a body portion having at its forward end hem turning means and between its ends uncurling means.
24. A sewing machine folder comprising 85 a body portion having at its forward end hem turning means and between its ends uncurling means, said uncurling means being formed integral with the body portion substantially midway of the length of the folder.
25. A sewing machine folder comprising 90

a body portion having at its forward end hem turning means and between its ends uncurling means, one at each side thereof, said uncurling means extending toward each other.

26. A blank for a sewing machine folder comprising a body portion having opposite side extensions separated from the forward end of the body portion by slots, each of 10 said extensions having its free end located substantially at an obtuse angle to its outer edge and said body portion having at its forward end a substantially V-shaped recess, which together with the angular formation of the ends of the extensions form 15 when the blank is folded means to permit the strip to be inverted or turned inside out.
27. A blank for a sewing machine folder comprising a body portion having opposite side extensions separated from the forward end of the body portion by slots, each of 20 said slots terminating in an enlarged portion at its inner end, said blank also having a projection adapted to form uncurling means at the inner end of each of said slots when the blank is folded.
28. The combination with stitch forming mechanism, of a folder, means for supporting 25 said folder with its longitudinal axis substantially at right angles to the line of stitching, said folder having guiding walls adapted to guide a binding strip and provided with space forming recesses at the 30 side edges thereof, and having the delivery end thereof shaped so that said strip may be inverted as it is led from the folder to the stitching mechanism and also having between the receiving and delivery ends 35 thereof means for turning the edges of the strip outwardly and backwardly upon the strip.
29. The combination with stitch forming mechanism of a folder, means for supporting 40 said folder with its longitudinal axis substantially at right angles to the line of stitching, said folder having guiding walls adapted to guide a binding strip and provided with space forming recesses at the 45 side edges thereof and having the delivery end thereof shaped so that said strip may be inverted as it is led from the folder to the stitching mechanism, and also having between the receiving and delivery ends 50 thereof means for turning the edges of the strip outwardly and backwardly upon the strip, said folder also having between its receiving and delivery ends means for folding 55 the binding strip between its edges.
30. The combination with stitch forming mechanism, of a folder, means for supporting 60 said folder with its longitudinal axis substantially at right angles to the line of stitching, said folder having guiding walls

adapted to guide a binding strip and provided with space forming recesses at the side edges thereof and having the delivery end thereof shaped so that said strip may be inverted as it is led from the folder to the stitching mechanism, and also having 65 between the receiving and delivery ends thereof means for turning the edges of the strip outwardly and backwardly upon the strip, said folder having uncurling means at the space forming recesses of the guiding 70 walls.

31. The combination with stitch forming mechanism, of a folder, means for supporting 75 said folder with its longitudinal axis substantially at right angles to the line of 80 stitching, said folder having guiding walls adapted to guide a binding strip and provided with space forming recesses at the side edges thereof and having the delivery end thereof shaped so that said strip may be inverted as it is led from the folder to the stitching mechanism, and also having 85 between the receiving and delivery ends thereof means for turning the edges of the strip outwardly and backwardly upon the strip, said folder having guiding walls 90 adapted to guide a binding strip and provided with space forming recesses at the side edges thereof and having the delivery end thereof shaped so that said strip may be inverted as it is led from the folder to the stitching mechanism, and also having 95 between the receiving and delivery ends thereof means for turning the edges of the strip outwardly and backwardly upon the strip, said folder also having between its receiving and delivery ends means for folding the binding strip between its edges, said folder having uncurling means at the space forming recesses of the guiding walls.

32. A sewing machine folder comprising a front and a back member spaced apart and bent at its forward end to fold the strip centrally thereof, one of said members having a pair of extensions overlapping the other and effective to fold the raw edges of the strip, said folder having means at its forward end effective to turn the strip inside out and feed it at an angle to its initial direction of feed, the said front and back members having space forming recesses at their edges whereby the rear portion of the folder is spaced apart from the front portion thereof at such edges.

33. A sewing machine folder comprising a front and a back member spaced apart and bent at its forward end to fold the strip centrally thereof, one of said members having a pair of extensions overlapping the other and effective to fold the raw edges of the strip, said folder having means at its forward end effective to turn the strip inside out and feed it at an angle to its initial direction of feed, the said front and back members having space forming recesses at their edges whereby the rear portion of the folder is spaced apart from the front portion thereof at such edges, the said front and back members being unconnected at such spaced portions.

34. A sewing machine folder comprising a pair of members bent upon themselves to form a front and a back member spaced

apart, said members being bent to hold a strip centrally thereof, one of said members having at its forward end a pair of extensions overlapping the other member and effective to fold the raw edges of the strip, and said members at each side thereof in the rear of said extensions having its edges unconnected, said folder also having its forward end effective to turn the strip inside 10 out and feed it at an angle to its initial direction of feed.

35. A sewing machine folder comprising a body portion constructed to fold a strip centrally thereof at its forward end and to 15 fold the raw edges of the strip and to permit the strip to be turned inside out and fed at an angle to its initial direction of feed, said body portion comprising a pair of members spaced apart and having the opposite edges of said members between the ends of the folder unconnected back of that part of the folder which is effective to fold the raw edges of the strip.

36. A blank for a sewing machine folder

comprising a body portion and a pair of extensions, one at each side thereof and joined substantially throughout its length to said body portion, said body portion having a substantially V-shaped recess at its end and each of said extensions having an inclined end adjacent to said recess, one inclined wall of said recess extending in a direction opposite to the inclined end of said extension, said body also having another pair of extensions in juxtaposition to said first extensions, and also having inclined ends running in the same direction as the inclined ends of said first extensions.

In testimony whereof we have hereunto signed our names to this specification in the presence of two subscribing witnesses, this twenty-sixth day of July, 1906.
